UNITED STATES PATENT OFFICE.

EDWARD C. BAYNES, OF BUFFALO, NEW YORK.

DESIGN FOR A HEAD OR FOOT BOARD FOR BEDSTEADS.

SPECIFICATION forming part of Design No. 25,417, dated April 21, 1896.

Application filed December 18, 1895. Serial No. 572,599. Term of patent 7 years.

To all whom it may concern:

Be it known that I, EDWARD C. BAYNES, a citizen of the United States, residing at Buffalo, Erie county, New York, have invented and produced a new and original Design for Head and Foot Boards of Metallic Bedsteads, of which the following is a specification, reference being had to the accompanying drawing, showing a part thereof.

10 The drawing herewith, consisting of a single figure, shows an elevation of my design.

The leading or characteristic features of my design are the two similarly-curved top rods which extend between the pillars of the head 15 or foot board or frame-piece of the bedstead and the filling-rods, which are connected at their upper ends with one of the said curved top rods.

Referring to the drawing, A A represent 20 the pillars, and B and C the curved top rods disposed between the upper ends of the pillars. The central portions of these rods are similarly curved upon arcs of circles having a common center, the two rods being parallel 25 to each other throughout their length.

D represents the lower rod extending between the pillars, and E the vertically-disposed filling-rods extending from the lower

rod D to the top curved rod B. The chills F are of ornamental design and are disposed at 30 the junctions of the filling-rods E with the rods D and B. Between the top rods there are the ornamental connecting-pieces, as the spindles G and rings H, which serve to give completeness to the design. 35

By the employment of the curved rods B and C between the pillars a chaste, pleasing, and distinctive design is produced.

In the drawing only one end piece or board of the bedstead is shown. This may be used 40 either as a head or a foot board, the difference between the two being that in the head-board the pillars and filling E are longer than in the foot-board.

Having described my design, what I claim 45 is—

The design for head and foot boards of metallic bedsteads, substantially as shown and described.

In testimony that I claim the invention 50 above set forth I affix my signature in presence of two witnesses.

EDWARD C. BAYNES.
